D. L. McCORKINDALE

PROCESS OF AND MEANS FOR DRYING PAPER

Filed Feb. 6, 1926

INVENTOR.

Duncan L. McCorkindale,

BY

Frank A. Cutler,

ATTORNEY.

UNITED STATES PATENT OFFICE.

DUNCAN L. McCORKINDALE, OF HOLYOKE, MASSACHUSETTS.

PROCESS OF AND MEANS FOR DRYING PAPER.

Application filed February 6, 1926. Serial No. 86,478.

My invention relates to improvements in the art of drying paper after it has received its bath of sizing, and the process consists primarily in carrying the paper between two felts under and over hot cylinders, and secondarily in passing the paper in direct contact with other hot cylinders, and in subjecting the paper to a cooling blast or blasts of air, the air blasts not being necessary in some cases, and the subjecting of the paper to the direct action thereon of hot cylinders not being necessary in some cases, in other words, either or both of the secondary steps may be omitted, while the means comprises, with a size box and size rolls, a plurality of upper and under drying cylinders and upper and under felts passing over and under the same, and preferably an additional drying cylinder or cylinders, which I term conditioning driers, and suitable conduits for discharging the cool air onto the paper, all as hereinafter set forth.

The primary object of my invention is to provide a process of and means for drying paper, and especially high-grade paper, after the same has received the sizing, in a continuous operation, and in a manner to prevent the evaporation of the sizing, and to cause said sizing to become set in the paper before the latter can come into direct contact with any hot roll or cylinder. I take the paper after it leaves the size rolls and without interruption or break in the process deliver it to the slitters, and thence to the cutter, or to the reel if the paper is to be wound into rolls.

Other objects are to dry paper, which has been saturated with sizing, in a very much more economical manner than when such paper is dried by the so-called method of pole drying, to reduce the time consumed in the drying process to an immediate delivery, and to produce results equal to or better than those produced by the aforesaid pole-drying method.

Other objects and advantages will appear in the course of the following description.

In carrying out my process, I prefer to make use of means such as are illustrated in the accompanying drawing, which is a diagrammatical view of the parts and members of a machine that embodies a practical form of my invention from a mechanical standpoint.

The left-hand end of the machine illustrated in the drawing is to be considered as

the front end thereof, and the right-hand end the rear end thereof.

In the drawing, a size box is represented at 1, guide rolls at 2—2, upper and under size rolls at 3, six drying cylinders at 4, three of such cylinders being above and in offset relationship to the other three, upper and under or top and bottom felts at 5 and 6, respectively, five guide rolls at 7 for said upper felt, and the same number of guide rolls at 8 for said lower felt, a pair of conditioning driers at 9 and an associated guide roll at 10, another guide roll at 11, upper and under slitters at 12, and an air pipe at 13 which has two discharge nozzles 14 and 15. A web of paper is designated by the numeral 16.

The size box 1 is at the front end of the machine. One of the guide rolls 2 is at the entrance to said box, and the other guide roll 2 is above the upper size roll 3. The lower size roll 3 is partly submerged in the sizing in the box.

The top felt 5 passes under each of the lower drying cylinders 4 and over each of the upper drying cylinders 4, and upwardly from the first lower drying cylinder 4 to and over the first guide roll 7, rearwardly from said roll to the third guide roll 7, partly around said third roll and forwardly to the second guide roll 7, partly around said second roll and rearwardly to the fourth guide roll 7, over said fourth roll and downwardly to and under the fifth guide roll 7, and upwardly to the third upper drying cylinder. The bottom felt 6 passes from the first guide roll 8 downwardly and rearwardly under the felt 5 on the first bottom drying cylinder 4, upwardly and over the first upper drying cylinder 4, between the same and the felt 5 thereon, downwardly and under the felt 5 on the second lower drying cylinder 4, upwardly and over the second drying cylinder 4, between the same and the felt 5 thereon, downwardly and under the felt 5 on the third lower drying cylinder 4, and upwardly and over the third upper drying cylinder 4, between the same and the felt 5 thereon, and downwardly under the fifth guide roll 8, forwardly to and up over the third guide roll 8, rearwardly to and up over the fourth guide roll 8, forwardly to and under the second guide roll 8, and upwardly to and over said first guide roll. Thus it is seen that the parts of the drying cylinders 4 with which the web

or paper 16 would ordinarily come in contact are covered with the two felts 5 and 6, and that said paper must, therefore, in passing in its tortuous course under and over 5 said drying cylinders, in the manner presently to be explained, be carried between said felts and thereby prevented from coming into direct contact with the cylinders. The drying cylinders 4 are heated in the 10 usual manner, and there may be more or less than six of them.

The drying cylinders 4 and the felts 5 and 6, with the guide rolls for said felts, are behind the size box 1 and size rolls 3. The 15 conditioning driers 9 are steam-heated drums or cylinders, and they with the guide roll 10 are behind the drying cylinders 4 and the felts 5 and 6, and one of said conditioning driers is directly behind the other, 20 while said guide roll is above the space between the two driers. There may be more or less than two of the driers 9.

The air pipe 13 is below the guide roll 11, and the latter is above and a little behind the rear conditioning drier 9. The 25 nozzles 14 and 15, with which the pipe 13 is provided, are arranged and adapted to discharge air onto the front and back sides, respectively, of the paper 16 as it passes upwardly from the rear conditioning drier 9 to the guide roll 11.

The slitters 12 are arranged one above the other, and the bottom slitter is directly behind the guide roll 11.

35 The web of paper 16 enters the size box 1 beneath the guide roll 2, and passes rearwardly under the bottom size roll 3 and up over and between said roll and the size roll 3 above. The rolls 3 press out the surplus 40 sizing from the paper 16 as it passes between said rolls, in the customary manner. From the upper size roll 3 the paper 16 passes up over the second guide roll 2, rearwardly and downwardly onto the bottom 45 felt 6 at the place where said felt passes over the first guide roll 8 and downwardly and rearwardly with said felt to the place where the two felts run together in front of the first lower drying cylinder 4. From 50 this point the paper is carried between the two felts 5 and 6 under and over the upper and lower drying cylinders 4, respectively and alternately, until it emerges from between said felts at the place where they separate behind the third upper drying cylinder. From the third upper drying cylinder 55 4 the paper passes down with the top felt 5 in front of the fifth guide roll 7, and then continues on downwardly to the front 60 conditioning drier 9 under which it passes. The paper then passes up over the guide roll 10, down under the rear conditioning drier 9, up over the guide roll 11, and rearwardly between the slitters 12. It is while 65 the paper is passing from the rear condi-

tioning drier 9 to the guide roll 11 that the cold air is discharged onto one or both sides thereof. By closing a valve 17, with which each of the nozzles 14 and 15 is provided, the air may be shut off from one or the 70 other of said nozzles, and thus applied to one side of the paper only, a condition which may be desired or required in some cases.

As the paper passes with and between the felts 5 and 6 under and over the drying cylinders 4, the sizing in and on the paper is prevented from evaporating and caused to dry and set. Direct contact at this time with the hard peripheries of hot cylinders would be disastrous. If additional drying of the paper be required, live steam is turned into the conditioning driers 9 with which the paper comes into direct contact after leaving the felts and being prepared by them for such contact, and the drying is thus completed, or, if not, the cool air is turned on and discharged onto the paper as soon as it leaves the rear conditioning drier.

The arrangements of the guide rolls 7 90 and 8, whereby the felts 5 and 6 are caused to travel considerable distances exposed to the air, is for the purpose of removing or eliminating moisture from said felts, and 95 keeping them in condition to dry the paper and the sizing thereon and therein as said paper passes in contact with the felts.

Preferably one of the felts is made of wool of a coarse texture.

If it be not desired to heat the paper after 100 it leaves the felts 5 and 6, the live steam is not turned into the conditioning driers 9, and in that case said driers serve merely as guide cylinders for the paper. In the event the conditioning driers would never be required, they might be omitted from the machine and other guiding elements for the paper substituted therefor; and, in the event no air blasts would ever be needed, the pipe 13 would be omitted; but preferably both 110 said driers and said pipe are provided, even though not always used.

It is now clear that the paper-drying process consists broadly in passing the paper, after the same receives the sizing, between the heated felts or felts which pass over hot drying cylinders; and that specifically said process consists in passing the paper from the size rolls between felts that are carried on hot drying cylinders, in passing said paper from said felts in direct contact with a hot conditioning drier or driers, and in passing said paper from said driers through or subjecting it to cooling blasts of air, or in passing the paper in direct contact with the heated conditioning driers without subjecting the same to the air blasts, or in subjecting the paper to the air blasts without first carrying the same in direct contact with heated driers.

When the conditioning driers 9 are employed, the temperature of the same is varied to whatever extent may be necessary in order to meet different conditions.

5. What I claim as my invention, and desire to secure by Letters Patent, is—

1. A process of drying paper consisting in passing the paper, after sizing has been applied thereto, between moving felts carried on heated drying cylinders, and in passing said paper from said felts into direct contact on one side with heated rotating conditioning driers while the other side of said paper is exposed to the air.

15. 2. A process of drying paper consisting in passing the paper, after sizing has been applied thereto, between felts carried on heated drying cylinders, in guiding said paper from said felts to slitters, and in blowing air onto said paper before it reaches said slitters.

25. 3. A process of drying paper consisting in passing the paper, after sizing has been applied thereto, between traveling felts carried on heated drying cylinders, and in guiding said paper from said felts through air currents.

30. 4. A process of drying paper consisting in passing the paper, after having sizing applied thereto, between traveling felts carried on heated drying cylinders, in guiding said paper from said felts to slitters, and in subjecting the paper on both sides to blasts of air before it arrives at said slitters.

35. 5. A process of drying paper consisting in passing the paper, after sizing has been applied thereto, between moving felts carried on heated drying cylinders, in passing said felts in direct contact with heated conditioning driers, and in subjecting said paper to air currents after it leaves said conditioning driers.

40. 6. In means for drying paper after sizing has been applied to the same, a plurality

of drying cylinders, felts carried by said cylinders and adapted to receive between them the paper after sizing has been applied thereto, rolls arranged to guide said felts to and from said cylinders, and a conditioning drier, back of said drying cylinders, to receive the paper in direct contact therewith after it leaves said felts, the paper being held by the pull thereon against said conditioning drier so that one side of the paper is exposed to the air.

55. 7. In means for drying paper, a plurality of drying cylinders, felts carried by said cylinders and adapted to receive between them the paper after sizing has been applied thereto, rolls to guide said felts to and from said cylinders, slitters, means to guide the paper from said felts to said slitters, and means to project air onto said paper before it reaches said slitters.

60. 8. In means for drying paper, a plurality of drying cylinders, felts carried by said cylinders and adapted to receive between them the paper after sizing has been applied thereto, rolls to guide said felts to and from said cylinders, a conditioning drier 70 with which said paper is carried in direct contact after leaving said felts, slitters, and means to project air onto said paper at a point between said conditioning drier and said slitters.

75. 9. The combination, in means for drying paper, with a size box, and size rolls, of a plurality of drying cylinders, felts carried by said cylinders, between which felts the paper is adapted to pass after receiving sizing from said rolls, rolls to guide said felts to and from said cylinders, conditioning driers, behind said cylinders, to receive in direct contact therewith the paper after it leaves said felts, slitters, and means intermediate of said driers and said slitters to project air onto the paper.
